ALF LYSHOLM, OF STOCKHOLM, SWEDEN, ASSIGNOR TO AKTIEBOLAGET LJUNGSTRÖMS
ANGTURBIN, OF LIDING-O-BREVIK, SWEDEN, A CORPORATION

TURBINE-DRIVEN LOCOMOTIVE

Application filed May 1, 1924, Serial No. 710,463, and in Sweden April 30, 1923.

It has previously been proposed in turbine driven locomotives to also drive the auxiliary aggregates, for instance feeding pumps, condensate pumps and the like by means of turbines, the exhaust steam from said turbines having been led therefrom in several different manners. Thus, for instance, the said auxiliary turbines have sometimes been connected in such a way that the exhaust steam from the turbine has been caused to pass wholly or partly through another turbine, or said turbines have been connected to the main turbine either in such manner that the exhaust steam from the auxiliary turbine has been led into the main turbine at such a place, where the back pressure is suitable for the auxiliary turbine, or in such manner that the auxiliary turbines have been fed with steam drawn from the main turbine at a suitable place. The main turbine has, substantially, obtained its steam directly from the steam boiler of the locomotive and has delivered the same directly to a condenser. Since several of the auxiliary aggregates, due to their nature, have to be controlled, in a manner, dependent on the main turbine, the control of the locomotive has hitherto been rather complicated.

The present invention relates to locomotives of the above-mentioned type and has for its object to facilitate the control of the locomotive, so that the control of the auxiliary turbine will follow directly upon the control of the main turbine, and consists in that the inlet part of one or more of the turbines adapted for running said auxiliary aggregates is connected to the steam boiler and that the exhaust pipe from said turbine or turbines is connected to the inlet part of the main turbine.

The invention is illustrated in the annexed drawing. In all of the figures only one auxiliary turbine is arranged according to the invention, however, it will obviously involve no difficulty to arrange several turbines in the same manner. Fig. 1 shows a locomotive with condenser, main and auxiliary turbines arranged according to the invention. Fig. 2 shows schematically a coupling diagram of an arrangement according to the invention, and Fig. 3 shows a modified form of embodiment

of the said arrangement. Fig. 4 shows diagrammatically a detail of the connection between the main turbine and the auxiliary turbine.

In Figs. 1, 2 and 3, 1 designates the steam boiler of the locomotive, 2 an auxiliary turbine adapted for running, for instance a machine or machines for forcing cooling air through the condenser. In the embodiment shown in Fig. 1, these machines consist of fans 21, driven by the auxiliary turbine 2 by means of a shaft 22 and bevelled gearings 23, but it is to be understood that centrifugal ventilators or the like may be used. The main turbine is indicated by the reference numeral 3 and 4 is the condenser. According to Figs. 1 and 2 the steam passes from the steam boiler 1 through a high pressure pipe 8 to a steam valve 5 common to both of the turbines 2 and 3 and thence through the pipe 9 to the auxiliary turbine 2. The blade system and the inlet part of said turbine are such that a small part only of the drop of pressure of the steam passing through the high pressure pipe 8 is utilized. From the auxiliary turbine 2 the steam is led through the pipe 10 to the main turbine 3 where the whole remaining drop of pressure is utilized, that is a drop of pressure from the pressure of the supply steam down to the vacuum in the exhaust pipe 11 to the condenser. This condenser may be of any known type, for instance be constructed as shown in the Patent No. 1,550,177. The exhaust steam of the main turbine thus enters a liquid receptacle, kept under vacuum, and then passes through several pipings into air cooled elements, where it is condensed. The condensate flows back again to the receptacle. By arranging according to the invention the auxiliary turbine between the steam boiler and the main turbine it is possible to control by means of one steam valve 5 the main turbine 3 as well as the auxiliary turbine 2. Obviously this is of great importance in case of the running of the auxiliary turbine being dependent on the running of the main turbine, which, for instance, is the case, when the auxiliary turbine, as shown in Fig. 1, is adapted to drive fans 21 for forcing the cooling air necessary for the condenser 3, since

the main turbine, obviously, should not be started without simultaneously forcing cooling air through the condenser. Another advantage gained by the invention is that the speed of the auxiliary turbine is regulated 5 automatically in accordance with the speed of the main turbine.

In the modification shown in Fig. 3 the high pressure pipe 8 is divided into two pipes 10 and 13 which by means of steam valves 5 10 and 5¹ lead to the auxiliary turbine 2. The exhaust pipe 10 from the auxiliary turbine 2 is likewise divided into several pipes 10^a, 10^b and 10^c, respectively (three branch pipes being shown in the drawing), which all open 15 into the inlet part of the main turbine 3, and two branch pipes 10^b and 10^c of which are provided each with a steam valve. The exhaust pipe 11 from the main turbine 3 opens, as before, directly into the condenser. The branch pipes 12 and 13 open each into the passages between a group of guide blades of the auxiliary turbine 2 which, as will be described in detail in connection with Fig. 4, 20 are so constructed that the steam delivered to the turbine 2 through the pipe 13 will, when passing through said pipe, be subjected to a greater drop of pressure than the steam delivered to the turbine through the pipe 12. 25 The drop of pressure in the first mentioned case is, preferably, so great that the pressure in the exhaust pipe 10 will obtain the same value as the vacuum in the condenser 4. Thus, by such means it is possible to drive the turbine 2 without simultaneously starting the 30 turbine 3. For that purpose the steam valve 5¹ is opened, while the steam valve 5 is held closed, the steam quantity delivered to the turbine 2 being subjected to such a great drop 35 of pressure that the same vacuum is produced in the pipe 10 as in the condenser 4 so that, consequently, no drop of pressure will be left to the main turbine. If, on the other hand, the steam valve 5 is opened, the steam supplied 40 to the turbine 2 will be subjected to a small drop of pressure only, so that a sufficient pressure remains for the running of the main turbine 3. By opening one or both of the valves in the pipes 10^b and 10^c the back 45 pressure after the turbine 2 may be varied and also the output of the two turbines 2 and 3. In the same degree as more of said valves 50 are closed, the back pressure after the turbine 2 is increased and the output of the said turbine with relation to the turbine 3 lessened. 55 When the branch pipes 10^a, 10^b and 10^c communicate with surfaces of the inlet part of the main turbine having different dimensions, the said variation of the back pressure after 60 the auxiliary turbine may be performed more smoothly by opening and shutting off the valves.

The above-mentioned arrangement will be more clearly apparent from Fig. 4. According 65 to said figure the turbine 2 consists of a

blade wheel 14 and guide blades 15 and 16. The said guide blades 15 and 16 are, as mentioned above, so constructed that the steam entering through the pipe 12 is subjected to a small drop of pressure only, when passing through the turbine, while the steam entering through the pipe 13 is subjected to a drop of pressure, for instance down to the vacuum in the condenser. The said action is performed so that the passages between the guide blades 15 do not get wider towards the blade wheel 14 and, consequently, no expansion of the steam will take place in the said guide blades, whereas the passages between the guide blades 16 get wider towards the blade wheel 14, so that the steam is subjected to an expansion, when passing through said guide blades.

According to Fig. 4 the exhaust pipe 10 from the turbine 2 is divided into two branch pipes 10^a and 10^b respectively, the branch pipe 10^a of which communicates with the guide blades 17 and the first blade wheel 18 of the main turbine 3. The branch pipe 10^b is controlled by a valve 19 through which steam may be supplied to the guide blades 20. If the valve 19 is closed, a higher back pressure after the turbine 2 exists than if said valve is open. Thus, in the former case the turbine 2 delivers a less quantity of energy relatively 25 to the turbine 3 than in the latter case.

Assuming that the turbine 2 drives fans for the cooling air of the condenser, the turbine should obviously deliver a greater amount of energy during the summer, when a greater quantity of cooling air is required, than during the winter, when the temperature is lower and thus the quantity of cooling air may be decreased. The branch pipes 10^a and 10^b are 30 preferably so chosen that the valve 19 need not be controlled at other occasions than when a change in weather has occurred, so that the said valve will during the summer be wholly or partly opened, while said valve will be closed more or less in the same degree as the 35 outer temperature drops.

Thus, according to the invention it is possible to control both turbines by a valve device common to both turbines. This is, as above mentioned, of great importance when the running of the auxiliary aggregate driven by the auxiliary turbine is dependent on the running of the main turbine, which is the case in the above chosen example, when the auxiliary turbine is used for running the fans of the condenser. Thus, it is advantageous with respect to steam economy that the quantity of the cooling air forced through the condenser is automatically adjusted in proportion to the steam delivered by the main turbine and that the auxiliary turbine is only driven, when cooling air is required.

However, a case may arise where it is only necessary to drive the auxiliary turbine without simultaneously driving the main turbine.

As mentioned above, this may be accomplished, when the main turbine stands still, in that the auxiliary turbine is only driven by steam through the pipe 13. The condition will be the same, when the main turbine runs idle on account of the locomotive, for instance when coasting on a down grade, in which case the steam to the auxiliary turbine 2 is likewise delivered only through the pipe 13. In this case, an advantage will also be gained by an arrangement according to the invention where the exhaust steam from the auxiliary turbine driven in the manner described, when passing through the main turbine, has a cooling action on said turbine, which is of great importance in order to prevent too high a heating of the main turbine due to the friction of the blades against the steam remaining in some cases in said turbine.

The invention is independent of the purpose for which said turbines are to be used, and several modifications may, obviously, be conceived, without departing from the scope 25 of the invention.

What I claim as new and desire to secure by Letters Patent of the United States of America is:—

1. In a turbine driven locomotive, a boiler 30 for a single pressure, a low pressure main turbine for driving the locomotive, an air forcing device, a high pressure auxiliary turbine for driving said air forcing device, a conduit connecting the inlet part of said auxiliary turbine with said boiler, and an exhaust pipe from said auxiliary turbine directly connecting same with said main turbine.

2. In a turbine driven locomotive, a boiler 40 for a single pressure, a low pressure main turbine for driving the locomotive, an air forcing device, a high pressure auxiliary turbine for driving said air forcing device, a conduit connecting the inlet part of said auxiliary turbine with said boiler, a plurality of exhaust pipes from said auxiliary turbine connecting same with said main turbine and a steam valve in certain of said exhaust pipes.

3. In a turbine driven locomotive, a boiler 50 for a single pressure, a low pressure main turbine for driving the locomotive, an air forcing device, a high pressure auxiliary turbine for driving said air forcing device, a conduit connecting the inlet part of said auxiliary turbine with said boiler, a plurality of exhaust pipes from said auxiliary turbine connecting same with said main turbine, a steam valve in certain of said exhaust pipes, said exhaust pipes being connected with portions of unequal size of the distributing or inlet part of said main turbine.

4. In a turbine driven locomotive, a boiler, a main turbine for driving the locomotive, 60 an air forcing device, an auxiliary turbine

for driving said air forcing device, a conduit connecting the inlet part of said auxiliary turbine with the boiler, said inlet part comprising two groups of guide blades, the passages between the blades of the one group 70 widening towards the blade wheel of the turbine, whereas the passages between the blades of the other group are of the same width throughout their entire length, and an exhaust pipe from said auxiliary turbine connecting same with the main turbine.

5. In a turbine driven locomotive, a boiler for a single pressure, a condenser, a low pressure main turbine for driving the locomotive, a device for forcing air through 80 the condenser, a high pressure auxiliary turbine for operating the air forcing device, a conduit connecting the inlet part of said auxiliary turbine with said boiler, and an exhaust pipe from said auxiliary turbine 85 directly connecting same with said main turbine.

6. In a turbine driven locomotive, a boiler for a single pressure, a condenser, a low pressure main turbine for driving the locomotive, 90 a device for forcing air through the condenser, a high pressure auxiliary turbine for driving the air forcing device, a conduit connecting the inlet part of said auxiliary turbine with said boiler, a plurality of exhaust pipes from said auxiliary turbine connecting same with said main turbine and a steam valve in certain of said exhaust pipes.

In testimony whereof I affix my signature. ALF LYSHOLM. 100
